BALL PROJECTING MANIKIN

Filed March 6, 1940

Fig. 2.

UNITED STATES PATENT OFFICE

2,199,181

BALL PROJECTING MANIKIN

Edward J. Collins, Los Angeles, Calif., assignor
to H. C. Evans & Co., Inc., Chicago, Ill., a corporation of Illinois

Application March 6, 1940, Serial No. 322,457

12 Claims. (Cl. 273—129)

This invention relates to amusement and game apparatus and has as its principal object the provision of an improved manikin peculiarly adapted to simulate the posture and certain movements of a human figure in propelling a ball or like projectile and particularly in bowling a ball in a manner familiar in the game of tenpins.

A further object is the provision of a manikin constructed with a movable arm portion for propelling a ball and having a leg portion providing a mounting for pivoting the manikin about a vertical axis with respect to a bowling alley, for example, together with mechanism concealed substantially within the leg portion and a part of the trunk for actuating the arm to propel a ball.

Yet another object is the construction of a ball-projecting manikin to simulate a human figure in stooping position, as in the action of bowling a ball, and providing the manikin with a pivoted arm to propel a ball, the arm being pivotally supported and actuated by a shaft extending in a direction between the opposite shoulders of the figure, and the upper part of the trunk of the figure being constructed in separable sections fitting together to journal the arm-pivoting shaft.

A further object is to provide mechanism situated within the separable portions and drivingly connected with the arm-pivoting shaft for actuation to pivot the same, the shaft-pivoting means further extending down through a leg portion of the figure for connection to an operating mechanism.

A further object is to provide, in such a figure, a leg portion having a foot portion which constitutes a pivotal mounting for the figure.

Other objects, advantages and novel aspects of the invention reside in certain details of construction as well as the cooperative relationship of the component parts of the illustrative embodiment described hereinafter in view of the annexed drawing, in which:

Fig. 1 is a side elevation of the manikin;

Fig. 2 is a vertical section along line 2—2 of

Fig. 1;

Fig. 3 is a side elevation with portions in section from a side opposite that shown in Fig. 1 and along line 3—3 of Fig. 1;

Fig. 4 is a bottom plan view of the upper section of the manikin casting;

Fig. 5 is a fragmentary perspective of the manikin operating means.

The novel ball-projecting or bowling manikin may be used in a variety of ball games in which it is desirable to simulate the action of a human

figure in propelling a ball relative to a playing field, the manikin being especially designed for use in a bowling game, such as described and claimed in my U. S. Patent No. 2,195,446, issued on patent application Serial No. 305,103, filed November 18, 1939.

As viewed in Fig. 1, the manikin consists of upper and lower separable sections 10 and 11 respectively, the sections being fitted together along a substantially horizontal juncture line indicated at 12, extending diagonally of the trunk portion of the figure.

The figure is preferably a casting of aluminum or other non-magnetic material for reasons which will appear hereinafter, and the figure is delineated in a stooped posture conformable to the position of a bowler in the action of propelling a ball at tenpins. In this posture, the left leg 13 of the manikin is in an approximately upright or vertical position relative to the plane of the mounting which, in this instance, would represent the bowling alley 14, while the right leg is bent at the knee with the foot 16 positioned appropriately behind the foot 17 of the left leg.

Correspondingly, the trunk portion 10 of the figure is thrust forward so as to substantially overlie the left leg 13, the left arm 18 dropping so that the hand 19 thereof may rest upon the knee portion of the left leg 13, it being observed that both the left and right shoulder portions 20 and 21 respectively (Fig. 2 also) are in nearly vertical alignment with the left leg.

Means is provided as a part of the left leg or foot structure for pivotally mounting the manikin to rotate about a vertical axis extending through the left leg 13, this means including, as shown particularly in Fig. 2, an inner tubular bushing 22 threaded at 23 into the left foot 17 and having a collar portion 24 and fitted into an outer bushing 25 seated in the playboard or bowling alley 14 and secured in position by a nut 26 with the lower portion 22a of the inner bushing projecting somewhat below the outer or mounting bushing to be clamped in a clamp bracket 27 which rotates with the manikin about an axis 40 coincident with the axis of the inner and outer bushings 22 and 25.

The clamp bracket 27, as shown in Fig. 5, is adapted to carry certain operating mechanism, and to this end is provided with an arm 27a to which is affixed a solenoid 28 having a plunger 29 connected by a special linkage 30 to a pivot arm 31 affixed (Figs. 2 and 3) to the lower end portion of a rock shaft 32 extended coaxially of the bushings 22 and 25 and up through the left leg 55

portion 13 of the manikin for the purpose of actuating a pivoted arm.

The clamp bracket 27 is also provided with an arm 33 which clampingly supports a permanent

- 5 magnet 34 having a polar end portion 35 disposed beneath a thin non-magnetic plate 36 covering an opening in board 14 to permit the polar end portion 35 to project as close as possible to the hand of the bowling arm, it being intended
10 that a magnetic ball shall be used with the manikin, and the magnet 34 serving to attract the ball when the same is delivered, by means not shown herein, toward the hand, the hand itself being of magnetically attractive material so that
15 there will be a magnetic circuit from the polar end 35 of the magnet through the ball into the hand, the ball nevertheless having sufficient freedom of movement to follow the hand to maintain said circuit effectively closed when the manikin
20 is adjusted by pivoting the same.

Pivotal movement of the manikin is effected by manipulation of a knob 38 pivotally mounted in board 14 and connected by a linkage 39 to another arm portion 40 of the clamp bracket 27.

- 25 The right or bowling arm 41 of the manikin is preferably constructed of iron or other suitable magnetic material and is pivotally mounted at its shoulder portion 21 by means of a stud shaft 42 secured to the arm by pin means 43 and extending through a bushing 44 in a cavity within the upper trunk portion of the figure, with the opposite end 42a of the stud shaft coming out of the trunk portion at a point slightly to one side of the shoulder portion 20 of the left arm
30 35 18, it being apparent that the right shoulder 21 would be thrown somewhat out of alignment with the left shoulder on a human figure in the act of bowling a ball.

- 40 The bowling arm 41 is pivoted by rotation of the shaft 32 responsive to attraction of the solenoid armature 29 from the normal position shown in Fig. 5, the rotative movement of the shaft being transmitted through a pinion 45 fixed thereon in the cavity at the top of the figure and meshing with a pinion 46 fixed to the stud shaft 42. It may be observed that a short tubular bushing 47 is positioned in the gap between the upper or knee portion of leg 13 and the chest portion of the figure for the purpose of shielding the passage of shaft 32 across this gap and for the further purpose of improving the bearing means at the upper end thereof.

- 45 The arrangement is such that the break or line of separation 12 between the upper and lower sections 10 and 11 of the figure passes through a horizontal diameter of the stud shaft 42, and the castings of both sections are therefore provided with suitable complementary formations 42b and 44a (shown in part in Fig. 4) coating 60 65 60 to provide a seating cavity for the bushing 44 on the one hand, and a bearing seat for the end portion 42a of the stud shaft on the other hand, when the sections are fitted and held together, as by screws S, so that the stud shaft 42 and associated parts may be conveniently assembled and removed, it being observed also that the upper and lower casting sections are provided with complementary cavity portions 48 and 49 in which the pinions 45 and 46 are conveniently housed.

- 70 As heretofore mentioned, the arm 41 is of magnetic material as is the hand portion 41a thereof, this hand portion being recessed to provide a socket 50, the curvature of which corresponds appropriately to that of the ball indicated at B 75 in Fig. 2, so that the magnetic circuit through

the hand portion and ball will be as effective as possible and in order further that the hand may properly engage the ball for purposes of propulsion.

The armature 29 is retracted to a normal position by action of a spring 51 (Fig. 5), and the bowling arm 41, in consequence, is pivoted to the limit of its retractive movement, determined by a pin 52 (Fig. 3) projecting from the leg just behind the elbow region of arm 41, the latter being provided with a resilient insert 53 of leather or the like to brake and deaden the return movement of the arm after each bowling action.

In the operation of the device it may be assumed that a ball B has been delivered, by means not shown, toward hand 41a of the bowling arm, the ball being drawn firmly against the socket portion 50 by action of magnet 34. The player may turn the knob 38 and pivot the manikin on bushing 22, which imparts similar movement to the entire bracket structure 27. The ball glides freely on the disc 36, but is nevertheless maintained firmly against the hand portion 41a.

Being satisfied with the adjustment of the manikin as aforesaid, the player will then operate a push button switch 55—56 (Fig. 3) to close an energizing circuit for the winding of solenoid 28, causing armature 29 to be attracted to rock the shaft 32 through the linkage 30—31, such movement of shaft 32 being transmitted through pinions 45 and 46 to the stud shaft 42, which causes arm 41 to move forward and propel the ball B down the alley. The arrangement of the solenoid and its linking means 30 connecting the same to the rock shaft 32 is such that the initial bowling movement of the arm is relatively slow and is thereafter accelerated to more nearly simulate the real motion of a bowler's arm.

The switch means 55—56 is only momentarily closed by the player, and thereafter the spring means 51 will restore the armature 29 and associated parts, including the arm 41, to its normal position.

The various advantages and objects of the invention may be accomplished by modifications of the particular embodiment specifically described herein, and it is intended that the appended claims shall include all equivalent arrangements fairly coming within their call.

Having thus described my invention, what I claim as new and desire to protect by Letters Patent is:

1. A ball projecting manikin comprising a body portion having a leg extending in approximately upright position, said leg having a foot portion and means cooperable therewith for maintaining the manikin on a support, said manikin having a trunk portion leaning over said leg to simulate the position of a bowling posture, said manikin having an arm pivoted on said trunk portion, drive means extending upwardly through said foot and leg portion and into said trunk portion, and means within said trunk portion drivingly connecting said drive means and said pivoted arm for actuating the latter in simulated bowling movement to propel a ball, said arm having a hand portion adapted to engage and propel a ball as aforesaid.

2. In a ball projecting manikin, means attached to a foot portion of the manikin mounting the same for movement about a vertical axis, an arm pivoted to the upper part of the trunk portion of the manikin, and means extending coaxially of said mounting means through said foot portion and the corresponding leg portion into the trunk

portion of the manikin and drivingly connected with said arm to pivot the same.

3. In a ball projecting manikin, a foot portion and a leg portion extending in approximately upright position therefrom, a trunk portion projected forwardly over said leg portion to simulate a stooping position, means attached to said foot portion for mounting the manikin for pivotal movement about a vertical axis extending through said leg portion, a pivoted arm attached to the upper part of said trunk portion and including a shaft element coacting therewith for movement to pivot the arm, said trunk portion including separable parts coacting to provide a bearing seat for said shaft when said parts are in assembled relation, and shaft means extending through said mounting means, said foot portion, said leg portion, and into said trunk portion and drivingly associated with said shaft for operation to pivot said arm.

4. In a ball projecting manikin including legs and a trunk portion, a trunk portion comprising separable parts, shaft means removably journaled between the junctural portions of said parts when the same are in assembled relation, and an arm mounted on said means and rotatable therewith, and means drivingly associated with said shaft within said trunk portion and passing through a leg portion of the manikin for connection with operating means for pivoting the arm.

5. A bowling manikin comprising a figure depicted in stooped position with one leg portion in substantially upright position and a companion leg portion stepped backwardly of the first leg portion, means operatively connected with the foot portion of said first-mentioned leg portion to mount the manikin for pivotal movement, said manikin having a trunk portion above said upright leg portion and thrust forward in stooped position, an arm pivotally attached to said trunk portion, said arm having a hand portion adapted to engage and propel a ball when the arm is pivoted, and means extending into said upright leg portion from the region of the foot thereof and into said trunk portion and operatively connected with said arm for actuation to pivot the latter.

6. A bowling manikin including a figure having a trunk portion inclined in stooped position to simulate the position of a bowler engaged in bowling a ball, said trunk portion consisting of upper and lower sections separable along a juncture line lying in an approximately horizontal plane, a shaft extending in a direction transversely of said trunk portion between the opposite arms of the manikin and journaled between said sections at the juncture line thereof, and a bowling arm mounted on said shaft and movable when the latter is rocked to simulate the movement of the bowler's arm in bowling action, shaft rocking means extended into said trunk portion, and mechanism housed within said sections and drivingly connecting said shaft with said shaft rocking means, said arm having a hand portion adapted to engage a ball positioned therebefore for propulsion when the arm is pivoted as aforesaid.

7. A ball projecting manikin comprising a body member simulating the appearance of a human figure in a stooping position with the left leg in substantially upright position and bent at the

knee to throw the trunk forwardly thereof with the left shoulder approximately overlying said knee, said figure having a right arm pivoted in the region of the shoulder thereof, said arm having a hand portion adapted to engage and propel a ball when the arm is pivoted, shaft means drivingly connected with said arm in said trunk portion, means attached to the foot portion of the left leg for supporting the manikin in pivotal movement about an axis extending through said leg, and a driving shaft extended through the left foot portion and leg coaxially of said mounting means and drivingly connected with said shaft within the trunk portion for actuation to effect pivotal movement of said right arm.

8. The device of claim 7 further characterized in that said second-mentioned driving shaft issues from the left leg in the region of the knee portion thereof and reenters said trunk portion for connection as aforesaid with the first-mentioned shaft means.

9. A ball projecting manikin comprising a body portion having a leg extending in approximately upright position, said leg having a foot portion and means cooperable therewith for maintaining the manikin on a support, said manikin having a trunk portion leaning over said leg, said manikin having an arm pivoted on said trunk portion, drive means extending upwardly through said foot and leg portion and into said trunk portion, and means within said trunk portion drivingly connecting said driving means and said pivoted arm for actuating the latter to propel a ball, said arm having a hand portion adapted to engage and propel a ball as aforesaid.

10. In a ball projecting manikin including a trunk portion, an arm pivoted on said trunk portion for movement to project a ball, said trunk portion including complementary separable parts, means providing a pivotal mounting for said arm and held in operative position between said complementary separable parts of the trunk portion at the junctural regions thereof, and means operatively associated with said pivotal mounting means for pivoting the arm in projecting action.

11. In a ball projecting device, a body including an arm mounted for pivotal movement relative thereto to project a ball, said body including a leg portion having a foot portion cooperating with a stationary mounting member to mount the same for pivotal adjusting movement about a vertical axis through said foot portion, and means for moving said arm in projecting action.

12. In a ball projecting manikin including a trunk portion with legs and a pivoted ball projecting arm on said trunk portion, means for mounting the manikin for adjusting movement about a vertical axis relative to a support, said means including attaching means situated at the foot portion of one of said legs and constructed for cooperation with a relatively stationary mounting means on said support whereby said manikin may be rotatively moved about a vertical axis through said foot portion and mounting means, and shaft means extending coaxially of the rotative axis through said foot portion into the manikin and drivingly connected with said ball projecting arm.

EDWARD J. COLLINS.
